CONTAINER

Andrew Weisenburg, Philadelphia, Pa., assignor
to Crown Can Company, Philadelphia, Pa., a
corporation of Pennsylvania

Application September 16, 1936, Serial No. 101,127

1 Claim. (Cl. 220—42)

The present invention relates to containers, particularly containers of the type having a longitudinal side seam, and the principal object of the invention is to provide such a container with 5 a seamless neck ring which will insure that the closure will maintain a tight seal, and which will at the same time permit a substantially full pouring opening from the mouth of the container.

Another object of the invention is to provide a 10 container having a resilient seamless neck ring, so that when a closure of the plug type is used, it will tightly engage the interior of the neck ring to maintain an effective seal.

Another object of the invention is to provide a 15 such a resilient neck ring so positioned within the end of the container that it will be supported by the side walls of the container when a plug type closure is inserted.

Another object of the invention is to provide a 20 seamless neck ring secured to the open end of a container by a double lock seam without having raw edges of metal exposed on the outside of the seam.

A further object of the invention is to provide a 25 a seamless neck ring which may be secured by a double lock seam to the open end of a container with the use of a chuck and seaming roll of simple construction.

Another object of the invention is to provide a 30 a seamless neck ring, which when seamed to the open end of a container by a double lock seam, will reinforce the open end of the container.

Another object of the invention is to provide a 35 seamless neck ring which is adapted to receive and be securely engaged by either a plug or cap type closure, provision being made for the latter type closure in that an external double lock seam of increased strength results from seaming a ring of the present invention to the open end of the container.

A further object of the invention is to provide a 40 neck ring which is fabricated from a minimum amount of metal and also to provide for the saving of metal by fabricating the neck ring and plug closure from the same blank of metal without wasting any of the same.

The container of the present invention is 45 adapted for use in the packaging of various materials, either liquid or dry. Among the dry materials such articles as cigarettes, mints, and coffee may be conveniently packaged in the container, and these articles may be packaged in the container with or without vacuum.

However, the improvements of the present invention are most outstanding when the con-

tainer is used for the packaging of liquid products such as paints, which are used directly from the container, being taken therefrom with a brush. When paints are used in this fashion, it is often desirable to reapply the closure with the expectancy of again removing the same, and the improvements of the present invention permit such use while maintaining an effective closure seal at all times.

The drawings illustrate several forms of the 10 invention, and it is understood that the disclosures of the drawings are for purposes of illustration and in no sense restrict the invention to the particular applications shown.

Figure 1 shows a blank of material such as 15 metal from which the seamless neck ring and the closure are fabricated.

Figure 2 shows one of the early steps in the 20 fabrication of the seamless neck ring and closure.

Figures 3, 4, 5 and 6 disclose succeeding steps 25 in the formation of the seamless neck ring.

Figure 7 shows a conventional can body having a 30 longitudinally side seam, to which the seamless neck ring and closure of the present invention is applied.

Figure 8 illustrates a further step in the manufacture of a container of the present invention, this figure showing the seamless neck ring positioned within the open end of a can body before the ring is secured thereto.

Figure 9 shows the manner in which a chuck 35 and seaming roll of simple construction may be utilized in securing the neck ring to a can body by a double lock seam.

Figure 10 shows an assembled can body and 40 seamless neck ring with a plug type closure positioned in the neck ring.

Figures 11, 12 and 13, 14 are similar to Figures 45 8 and 9, showing modified forms of the invention.

Figures 15, 16 and 17, 18 disclose modifications 45 of the seamless neck ring.

Figures 19, 20 and 21 disclose successive steps 50 in forming the seamless neck ring in accordance with a modification of the method disclosed in Figures 1 to 6 inclusive.

Figures 22, 23 and 24 show successive steps 55 employed in the formation of the plug type closure, starting with the blank resulting from the operation illustrated in Figure 2.

Figure 25 is a side elevational view of the closure 60 showing its application to a container.

Figure 26 illustrates the manner in which an 65 outside cap such as a conventional crown cap, may be used in covering a container employing a neck ring of the type disclosed in Figure 18.

In the manufacture of containers, particularly containers for such liquids as paints, it is essential that closure means be provided which will tightly seal the open end of the container. After the contents of the container have been partially used, it may be necessary to reapply the closure, and an effective seal is required after this reapplication to prevent the contents of the container from drying out. In the manufacture of metal containers such as cans, it is conventional to employ a side seam extending longitudinally throughout the length of the can, and if ordinary type closures are used in conjunction with such containers, leakage will result at the side seam if it is attempted to replace the closure after the can is initially opened.

To meet this difficulty it has been the practice to equip cans having the longitudinal side seam with some form of seamless neck ring, the ring being adapted to receive a closure of the plug type to provide an effective seal therewith.

These containers are usually equipped with a seamless neck ring such diameter that it extends from the side wall of the container inwardly toward the axis thereof a material distance, so that free flow through the open end of the container is prevented. This type of ring usually has a flat upper surface extending inwardly over the open end of the container terminating in a downwardly directed flange which provides a sealing area for the reception of a plug type closure. Such a construction results in a pocket being formed around the outside of the closure receiving flange, in which some of the liquid is trapped when the contents are flowed from the container or when the container is shipped in inverted position. In connection with the use of paints, such liquids usually solidify resulting in a material wastage of the same. The construction and manner of assembly of the seamless rings of the present invention results not only in a tight closure for the open end of the container, but also in an arrangement which permits substantially a full flow opening from the container mouth, without the paint collecting within a pocket around the sealing ring and within the can. The construction of the seamless ring and its arrangement at the open end of the container also insures that no paint will collect on the top of the can around the seamless ring, during the time when the paint is being taken from the container with a brush.

In Figure 1, 10 designates a blank of metal preferably circular in form if the container is of cylindrical shape, which is generally the case. Blank 10 is first stamped or otherwise formed into substantially hat shape as shown in Figure 2, and this hat shaped blank is severed along its cylindrical portion to form a seamless ring R and a plug type closure C. As illustrated in Figure 2, the blank may be cut along the diametrical plane 11.

After the above severing operation, the seamless ring blank R is in the form shown in Figure 3. The lower end of the blank R, as viewed in Figure 4, is then bent outwardly and upwardly conveniently in successive steps, as shown in Figures 4, 5 and 6, to shape the seamless ring into its final condition before application to the container. During and after these steps, the seamless ring comprises a central portion 13, an upper flanged portion 14 and a lower outwardly and upwardly bent portion 15, all for a purpose which will be hereinafter described.

By "upper" and "lower" I mean to designate the relative positions of portions 14 and 15 with re-

spect to the central portion 13, when the sealing ring is in the position illustrated in Figures 4, 5 and 6, which will be the normal position of the ring when it is positioned within a container and when the latter is in its normal upright position. 5

As illustrated, the lower portion 15 may be bent outwardly through an angle of 45°, as shown in Figure 4, further bent upwardly to the 90° position of Figure 5, and then bent through an additional angle of 45° or more to the position shown in Figure 6. The portion 15 may be bent to a greater or less extent toward the central portion 13 as desired, from the position shown in Figure 6 to, for instance, a position in which the portion 15 would lie substantially parallel and flat 15 against the outer wall of central portion 13. At any rate, it is desirable to have portion 15 flare outwardly from portion 13 some slight extent for a reason which will later appear.

Figure 7 shows a conventional container such as a metal can 17 which is formed from a rectangular blank of material, the edges of which are connected by a longitudinal seam 18, which usually is of a lock type. The upper end of the container is flanged outwardly as at 19 for the securing of the seamless neck ring in a manner which will later appear.

It will be apparent that by reason of the distortion of the cylindrical surface of the container caused by the side seam 18, it is difficult to tightly seal the open mouth of the can with a removable closure, such as one of the plug type. Consequently, it is necessary to provide some means for making the inside of the open end of the container uniform in contour and this is accomplished by providing a seamless neck ring of the type disclosed in the present application.

In Figure 8, the seamless neck ring as formed to the condition of Figure 6, is shown positioned in the open end of the container A, with the upper flange 14 of the ring resting upon the outwardly turned flange 19 of the can. When the ring is in this position, it will be noted that the central portion 13 thereof is closely adjacent to and in substantially parallel relation with the inner wall 45 of the container A, and that the outwardly and upwardly bent portion 15 is disposed between the inner wall of the container A and the outer wall of the central portion 13 of the ring.

When the parts are in this condition, the ring 50 may be secured to the container body in any convenient manner, but preferably as shown in Figure 9 by rolling the flanges 14 and 19 of the ring and container respectively into a double lock seam. In rolling the double lock seam, provision must be made for supporting the interior of the ring during the operation of the seaming roll B, which is forced inwardly against the flanges 14 and 19 and is of such contour that it bends said flanges down into the double lock seam of Figure 60 9 in a manner well known in the art. To support the interior of the ring and container during the seaming operation, a chuck D of simple construction may be used, said chuck being disposed within the seamless ring and being 65 adapted to provide an abutment against which the seaming roll will operate. By reason of the fact that the seamless ring lies closely adjacent the wall of the container, a chuck of relatively simple form may be used, and said chuck may be 70 inserted into the open end of the container as shown. It will be observed that the chuck D tapers inwardly and downwardly on its outer wall where it engages the central portion 13 of the seamless ring, so that there will be no appreciable 75

inward bending of the upper end of the body A which might cause leakage through the seam. However, in Figure 9 a somewhat exaggerated inward bending of the body is shown at 20, it being apparent that the upper end of the body will be forced in over the upper end of the portion 15 of the ring until the metal plies of the double lock seam are compressed into intimate engagement.

By reason of the utilization of the tapered 10 chuck and the configuration of the seaming roll B, it will be apparent that the rolling of the double lock seam will not flatten the outwardly and upwardly turned portion 15 against the wall of the container or against the central portion 15 of the ring to such an extent that all of the resiliency in portion 15 will be removed. That is, the end of the bent up portion 15 will bear 20 against the inner wall of the container, giving the lower end of the central portion 13 of the seamless ring a degree of resiliency, and the bent up portion 15 will provide a spring like resistance to the expansion of the lower end of the portion 13 of the ring when a plug type closure is inserted.

25 It will be further noted that portion 15 will not be flattened parallel with central portion 13, but joins with portion 13 at an acute angle thereto, leaving an open space between the two portions. This open space is relatively narrow where portions 15 and 13 join one another, and widens 30 toward the upper end of portion 15.

It will be noted that the bent up portion 15 of Fig. 9 engages the inner wall of the container at an acute angle thereto, so that the resiliency 35 of the lower end of the ring is not destroyed, as would be the case if the portion 15 were disposed at right angles to the central portion 13, and engaged the inner wall of the container at right angles thereto.

40 The closure is positioned within the seamless ring as shown in Figure 10, said closure having been formed from the blank C cut as in Figure 2, by following successive steps as illustrated in Figures 22, 23 and 24. The closure may be centrally bent to have a dome-shaped portion 24, which prevents adjacent containers from becoming 45 stuck together when stacked in a manner well known in the art, as will be obvious from the construction.

50 The outer engaging wall of the plug closure C may be vertical or it may taper outwardly slightly from the lower end thereof toward the upper bead 25 of the closure. At any rate, the diameter of the outer wall of the closure will be preferably 55 slightly greater at its lower end than the inner diameter of the lower end of the ring 13, when the closure is removed. When the closure is inserted, the lower end of the central portion 13 will be flattened outwardly against the upturned

60 portion 15 of the ring, the latter being supported by the inner wall of the container A, but capable of flexing movement with respect thereto, in view of the fact that the end of the upturned portion engages the wall at an acute angle. This resiliency will provide a tight seal between the closure and ring and will permit the closure to be reapplied to form a tight seal after the closure 65 has been initially removed. As shown in Figure 10, the lower end of the closure C moves downwardly beyond the lower end of the ring when the closure is inserted, and any compression of the lower end of the closure caused during the insertion will be relieved after complete insertion, permitting the lower end 26 of the closure to expand 70 outwardly to a slight extent beneath the

lower edge of the ring, thus further insuring a tight seal.

When the closure is in inserted position as in Figure 10, the bead 25 thereof will rest upon the upper edge of the double lock seam, thus limiting 5 the inward movement of the closure. A coin or other implement may be inserted between the bead 25 and the upper edge of the can to assist in removing the closure.

When the closure is removed, the outwardly 10 and upwardly bent portion 15 will cause the lower end of the ring to spring from its compressed position of Figure 10 to its relieved position of Figure 9.

In Figures 11 and 12 a modification of the invention is disclosed in which a sealing compound 30 is employed between the flange 14 of the seamless ring and the flange 18 of the container body. Any well known sealing compound may be used, and it may be flowed onto the lower surface of 20 the flange 14 when the ring is in inverted position and allowed to solidify, after which the ring may be positioned on the container as shown in Figure 11. When the double lock seam is rolled, as shown in Figure 12, the sealing compound will 25 be compressed within the folds of the double lock seam, further insuring against leakage. While it may be desirable in some cases to utilize this sealing compound, it has been found that a tight seal may be formed by practicing the present in- 30 vention without the use of the same.

In Figures 13 and 14 a modification of the invention is shown wherein the upturned portion 15 of the ring is bent upwardly until it lies substantially flush against the outer wall of the 35 central portion 13 of the ring, and when this type of seamless ring is positioned within the mouth of the container, the up-turned portion 15 will be substantially in complete surface contact with the outer wall of central portion 13 40 and the inner wall of the container. When using this construction, a chuck of increased taper may be employed when the double lock seam is formed, so that the inner wall of the central portion 13 will taper inwardly and downwardly 45 to a greater extent than as disclosed in Figure 9. In this arrangement, the upper end of the portion 15 will abut against the inner wall of the container at an acute angle thereto, and at a sufficient distance above the lower end of portion 50 13 to form a fulcrum therefor. The lower end of portion 15 where it merges with the lower end of central portion 13 will be spaced slightly from the inner wall of the container, so that the lower bend of the seamless ring may be expanded 55 outwardly around said fulcrum during insertion of the closure, providing resiliency which will result in intimate engagement of the closure with the ring.

In the above described embodiments, it will 60 be noted that the double lock seam is of substantial size, having a vertical dimension substantially half as long as the length of the central portion 13 of the neck ring. It will also be noted that said seam extends downwardly 65 substantially to the transverse plane through the axis of the container in which the end of the upturned portion 15 is located.

A further modification of the invention is disclosed in Figures 15 and 16, in which embodiment the outwardly bent portion 35 of the ring extends upwardly to substantially the upper end 70 of the container body as shown at 36. Such an arrangement, while employing an additional amount of metal, will increase the strength of 75

the mouth of the container and will result in a stronger double lock seam. In this modification, as in the forms of the invention hereinbefore described, a tapered chuck will be used during the rolling of the double lock seam, so that the lower end of the upwardly bent portion 35 of the ring will not be entirely flattened against the inner wall of the container during the rolling of the double lock seam, and resiliency will be provided adjacent the lower end of the ring to permit tight engagement with the inserted closure.

A further modification of the invention is shown in Figures 17 and 18. In this form of the invention, the outwardly turned portion 37 of the ring extends upwardly throughout substantially the length of the central portion 13, and is then bent outwardly through an angle of approximately 90°, forming a flange 38 which lies between the upper flange 14 of the seamless ring and the horizontal flange 18 of the container body, as shown in Figure 17. When this form of the ring is assembled as shown in Figure 17, the double lock seam may be rolled as hereinbefore disclosed. As in the other forms of the invention, a tapered chuck may be utilized in order that the desired resiliency will result at the lower end of the ring. It will be apparent that in this form of invention, a more bulky and stronger double lock seam will result, although appreciably more metal will be necessary in the formation of the seamless ring.

It will be noted in the above described embodiments, that the central portion 13 of the neck ring is smooth and straight on its interior and evenly tapers downwardly and inwardly from the end of the body to where the portion 15 is bent upwardly therefrom, so that said bend is slightly spaced from the inner wall of the container, the neck ring thereby being resilient at said bend as the latter is adapted to yield outwardly upon the insertion of a closure of the plug type into said ring.

While it is more economical to form the seamless ring and closure from the same blank as disclosed in Figures 1 to 6 and 22 to 24 inclusive, the seamless ring alone may be formed from a blank of metal as shown in Figures 19, 20 and 21. In these figures, the initial flat blank is shown at 40', and this blank may be stamped into the hat shaped form disclosed in Figure 20, after which the lower horizontal portion 40 of the hat shaped blank may be cut away as shown in Figure 21. The blank R resulting is of the same configuration as shown in Figure 3, and this blank may then be subjected to the steps illustrated in Figures 4, 5 and 6 to form the seamless ring. The removed blank 40 may then be disposed of, or it may be used in the formation of seamless rings, closures and the like for smaller containers.

In Figure 25, a closure as formed in Figures

22-24 is shown applied to a container. The bead 25 of the closure may be flattened at spaced points shown at 25', in order to permit the insertion of a tool beneath the bead to assist in removing the closure.

In Figure 26, an application of the invention is disclosed in which the container A may be sealed by an outside cap closure such as a conventional crown cap 45. It will be observed that a seamless ring and double lock seam of the type disclosed in Figure 18 is used, it being evident that the increased bulk of the seam formed will provide a sufficient shoulder as at 46 on the lower edge of the double lock seam to be gripped by the indentations 47 in the lower skirt 15 portion of the crown cap. While this form of the invention lends itself most admirably to the reception of an outside cap closure, the forms of seamless rings shown in Figs. 13 and 14 might also be used with an outside closure.

The invention thus provides a seamless ring which will permit sealing of the container by either an inside plug type closure or an outside cap type closure. It will be evident in Figure 26 that a tight seal will be formed at the upper edge 48 of the double lock seam, by the engagement of this edge with the packing disposed within the top of the crown cap 45.

Various modifications of the constructions shown herein may be made without departing from the scope of the invention.

I claim:

A cylindrical container having a body formed with a side seam, a seamless neck ring in an end of said body against the inner wall thereof to provide a substantially full pouring opening from the container, said ring having a central portion fitting within the end of the body, an upper portion secured to the edge of the body and a lower portion bent outwardly and upwardly between the inner wall of the body and the outer wall of the central portion of said ring, the end of said outwardly and upwardly bent portion contacting the inner wall of the body at an acute angle thereto a sufficient distance above the bend of said ring to form a fulcrum at the point of contact for said ring at its bend, the central portion of said ring tapering downwardly and inwardly from the end of the body to the bend of the lower portion of said ring to slightly space said bend from the inner wall of the container, said ring being thereby resilient at its bend and adapted to yield outwardly thereat, said container being adapted to removably receive a closure of the plug type within said ring, which closure engages said ring at its bend and expands the same around said fulcrum to form a tight seal between the closure and said ring, the bend of said ring being adapted to spring inwardly from the container wall when the closure is removed.

ANDREW WEISENBURG.
